APPARATUS FOR DEPOSITING MARSHMALLOW, DOUGH, BATTERS, AND THE LIKE

Earle T. Oakes, Douglaston, N. Y., assignor to
The E. T. Oakes Corporation, Islip, N. Y., a corporation of New York

Application February 20, 1951, Serial No. 211,961

11 Claims. (Cl. 107—29)

1

This invention relates to improvements in depositing devices and it relates particularly to an improved form of depositor for depositing dough, batters and the like to produce vanilla wafers, pound cake, layer cake, sponge cake, and so forth and for depositing marshmallow, jams, jellies and the like on cookies or cakes which are supported by a continuously moving conveyor during the depositing operation.

Generally, two types of depositors are in use in the bakery industry. The most common is the intermittent type of depositor in which a conveyor adapted to receive or support articles is moved intermittently beneath a depositing hopper. The other type includes a continuously moving conveyor and a depositing hopper which is reciprocated lengthwise of the conveyor to enable the coatings or toppings to be deposited on the continuously moving articles.

Both of the prior types of depositors include relatively large hoppers having open tops to permit the material, for example, marshmallow, to be poured into the top of the hopper. With the intermittent type of depositor, the conveyor with the articles thereon is advanced until a row of cookies or the like is disposed below the depositor so that the material can be applied to the articles during the dwell period of the conveyor. With this arrangement it is difficult to obtain high operating speeds because of the stop-start action of the conveyor.

With the continuous type of depositor, the hopper is reciprocated, but due to its very substantial weight, in combination with the material therein, it is difficult to obtain an operating rate higher than about 50 strokes of the hopper per minute.

One of the great disadvantages of both the intermittent and continuous depositors is the difficulty maintaining sanitary conditions and uniformity in the characteristics of the material being deposited. Inasmuch as the prior hoppers are open, a large surface area of the material is exposed to contamination from outside sources. Not only do dust and contaminants settle on and stick to the material in the hopper but the operators very frequently put their hands in the material and often scrape scrap back into the hopper. Moreover, in the case of marshmallow and jelly toppings, exposure to the air causes the material to dry out and become relatively stiff. When a new batch of the material is introduced into the hopper, the operator stirs the fresh batch in with the old, using either his hands or a paddle. Inasmuch as such a mixture of old and fresh batches cannot possibly be uniform under the conditions normally encountered in bakery operation, this uneven mix of the material results in uneven and misshapen deposits. This makes necessary the adjustment of the depositor at short intervals to maintain the deposits reasonably uniform in weight and shape.

2

When the material being deposited is a batter or a dough, the mixing of the old material with the fresh material causes streakiness in the resulting products and an uneven texture in the cookies or cakes.

The present invention relates to an improved type of continuous depositor, that is, a depositor having a continuously moving conveyor, which overcomes the disadvantages of the prior depositors pointed out above.

Generally, the new depositor includes a light weight manifold provided with a plurality of depositing nozzles, the manifold being connected by means of flexible conduits to a separate source of supply of the fluid material so that this material is introduced substantially continuously into the manifold through a closed system. The source of the material may be a continuous mixing device of the type disclosed in my copending application Serial Number 749,556, filed May 21, 1947, now abandoned. It may consist of one or more pressure chambers from which the material is forced continuously by air pressure or the like, or it may consist simply of a pump.

20 The manifold is carried by an arrangement of slides movable along right angularly related paths so that the manifold can move toward the conveyor, then travel with the conveyor at the same speed while the material is being deposited, then 25 move away from the conveyor after the nozzles have been closed to break off the stream of material at the nozzles and then return counter to the direction of movement of the conveyor to continue through another cycle. Due to the light 30 weight manifold and its relatively small capacity as contrasted with the prior hopper mechanisms, it is possible to move the manifold at a much 35 higher speed and thereby increase the rate of production of the machine severalfold over the prior continuous or intermittent depositors.

Another marked advantage of the depositor is that it affords a completely closed system for the material being deposited, thereby reducing contamination to a minimum.

40 The parts of the manifold and its connections are easily disassembled for efficient cleaning and easily adjusted to control the size and the shape of the deposit.

In addition to the above, the manifold may be 45 provided with the partition elements which enable materials of different colors or flavors to be deposited simultaneously.

Moreover, adjustment of the individual nozzles 50 enables very uniform deposits to be maintained over long periods of operation so that adjustment of the machine during its operation is infrequent.

For a better understanding of the present invention reference may be had to the accompanying drawings in which:

Fig. 1 is a view in side elevation of a typical machine embodying the present invention with a

portion of the frame broken away to disclose details of construction and disclosing diagrammatically the supply source for the material to be deposited;

Fig. 2 is a plan view of the machine with the conveyor belt and the depositing manifolds removed to disclose the operating mechanism;

Fig. 3 is an end view of the machine;

Fig. 4 is a view in elevation and partly in section of the depositing manifold; and

Fig. 5 is a view in section taken through one of the nozzles to illustrate an adjustment feature thereof.

A typical depositor may include a supporting framework of any desired design or size, depending upon requirements. As illustrated in Figs. 1 to 3, a frame 10 may include the side frame members 11 and 12 which consist of flat plates joined by suitable cross braces 13, 14 and 15. Adjacent to the opposite ends of the frame 10 are rotatably mounted the roller 16 and the nose plate 17 which support a conveyor belt 18 having its upper flight above or about on a level with the upper edges of the side frames 11 and 12. The upper flight of the conveyor belt 18 may be supported by means of a guide plate extending lengthwise of the side plates to prevent sagging of the upper flight of the conveyor. The lower flight is kept out of contact with the cross-braces and the like by means of one or more rollers 19. The conveyor 18 can be tensioned properly by adjusting the nose plate 17 lengthwise of the machine, a handwheel 17a being provided for this purpose. The belt can also be adjusted by means of a handwheel 17b at the opposite end of the frame member 11 which adjusts a roller toward and away from the lower flight of the belt.

Adjacent to the left-hand end of the frame 10 is a magazine type of hopper 20 which, as shown in Fig. 3, may have a plurality of separate compartments 21 each adapted to receive a stack of wafers, cookies, or the like to receive a deposit or topping of marshmallow, jelly or the like. The hopper 20 is of a conventional type well known in the art. It may be supported above the conveyor belt by means of the brackets 22 and 23 extending upwardly from the side plates 11 and 12 of the frame.

Overlying the conveyor 18 adjacent to the hopper 20 is a feeding plate 24 which is reciprocated back and forth to dislodge the lowermost wafers successively from the compartments 21 and place them in spaced rows transversely of the conveyor 18. The plate 24 is joined at its ends to push rods 25 and 26, Figs. 1 and 2, which are driven in a manner to be described hereinafter. The push rods 25 and 26 are guided in the guide lugs 27, 28 on opposite sides of the frame plates 11 and 12.

The rows of wafers pass beneath the depositing devices 29 and 30 (Fig. 1) to receive a topping of one or more materials and are finally discharged at the right-hand end of the frame 10 over the nose-plate 17 onto a delivery table, not shown.

The depositing devices 29 and 30 are alike and only the device 29 will be described herein in detail. Corresponding parts of the device 30, when referred to, will be identified by a primed corresponding reference character. The device 29 includes a depositing manifold 32 which consists of an elongated tubular member having removable end closure plugs 33 and 34. On the under-surface of the tubular member 32 is an elongated housing 35 which consists of an upper perforated plate 36 and a lower nozzle receiving plate 37. The upper plate 36 is provided with a groove 38.

facing the nozzle plate 37 to receive a slide valve 39 which extends lengthwise of the groove 38 from its open right-hand end. The upper plate 36 is provided with a plurality of openings 40 which are adapted to be aligned with corresponding openings 41 in the slide valve 39 when the latter is moved to the left and out of alignment when the slide valve is moved to the right.

The lower nozzle receiving plate 37 is provided also with the openings 46 substantially in alignment with the openings 40 and is provided with recesses for receiving the upper cylindrical flange portions 42 of the nozzles 43.

As shown in Fig. 5, each nozzle 43 has a downwardly extending tubular portion 44 and an inclined central passage 45 which can be brought into or out of the alignment with its corresponding opening 46 in the lower plate 37 by bodily rotation of the nozzle 43. The flange portion 42 of the nozzle may be provided with a groove 47 for receiving a packing and the nozzle may be retained in position with capacity for rotation by means of a retaining plate 48 secured to the under side of the plate 37 by screws or in any other suitable way. By rotating the nozzle 43, the inlet end of the passage 45 can be brought fully into alignment with the opening 46 or completely out of alignment with this opening to thereby regulate the flow of the material through the nozzle.

The material to be deposited is supplied to the manifold 32 by means of a plurality of flexible conduits 50, 51, 52, and 53 (Fig. 4) which are connected to suitable couplings 55 along the length of the manifold. The opposite ends of the conduits 50 to 53 may be connected to a distributing manifold 56 which, as illustrated in Fig. 1, may be connected to a suitable source 57 of the material under pressure. If desired, the material can be introduced through one end of the manifold 56 by means of a flexible tube, providing the material is sufficiently fluid and the nozzles are adjusted properly.

Inasmuch as it may be desired to deposit two different kinds or colors of material through the same depositing manifold, a partition structure consisting of an elongated rod 58 having a series of partitions 59 along its length may be inserted into the depositing manifold 32 and held in position by means of the end closures 33 and 34. By positioning the partitions between the several couplings 55 and between the several nozzles 43 and connecting the alternate couplings 55 or different groups of couplings to different manifolds 56 or sources of supply, it is possible to supply two or more different kinds, colors, or flavors of material to the depositing manifold without mixing them so that several different products may be produced simultaneously with the same machine. Also, with fluid materials, different colors or flavors of these materials can be introduced into opposite ends of the manifold, and a separating partition inserted between the ends of the manifold to keep the materials apart. Thus, it is possible to produce cookies having several different kinds of toppings or coatings simultaneously.

The manifold 32 is supported at opposite ends by means of slide blocks 60 and 61 which are supported and moved in a manner to be described hereinafter.

Referring now to Figs. 1 and 2, the drive mechanism for the depositor will now be described. The drive mechanism includes an electric motor 62 which is slidably supported by means of the brackets 63 and 64 on a pair of spaced guide rods.

65 and 66 for movement lengthwise of the frame 10. The guide rods 65 and 66 are mounted on the cross braces 13 and 14 extending between the side frames 11 and 12. The bracket 64 is provided with an internally threaded bushing 69 receiving a threaded shaft 70 which is journalled for rotation but held against axial movement in a frame member 71 (Fig. 2). The inner end of the shaft 70 carries a bevel gear 72 which meshes with a pinion 73 on the inner end of the shaft 74. The shaft 74 has a handwheel 75 on its outer end and is supported for rotation in the bracket 76 and the bearing 77 carried by the frame. The handwheel 75 enables adjustment of the motor lengthwise of the frame to vary the speed of a speed reduction unit 78, also supported by the cross member 14. The motor 62 drives an expansible cone pulley 79 which receives a V-belt 80 for driving the pulley 81 at the input end of the speed reduction unit 78. The two cone elements of the cone pulley 79 are normally urged together in a known way by means of a spring mechanism 82 so that adjustment of the motor to the right, as viewed in Fig. 2, allows the belt to move out toward the peripheries of the cones and causes the pulley 81 to be driven faster. Adjustment of the motor to the left decreases the speed of the pulley 81 and the speed of the output shaft 83 of the reduction unit.

The output shaft 83 is provided with a sprocket 84 which drives the sprocket 85 on the cross shaft 86 by means of a chain 87. The shaft 86 is rotatably mounted in the frame plates 11 and 12 above the motor and has a sprocket 87a at its upper end, as viewed in Fig. 2, for driving the sprocket 88, connected to the roller 16, by means of a chain 89. The system therefore provides a direct but variable speed drive between the motor 62 and the conveyor belt 18 to enable the speed of the conveyor belt to be varied substantially.

The output shaft 83 of the gear reduction unit carries a second sprocket 90 which drives by means of a chain 91, a sprocket 92 on the cross shaft 93. The latter is rotatably mounted in suitable bearings in the frame members 11 and 12 as shown in Fig. 2. The shaft 93 is the main drive shaft for the depositor and the wafer or cookie feeding plate 24. As best shown in Fig. 1, the shaft 93 carries a crank disc 94a. The crank pin 95 on the disc 94a is connected by means of a link 97 to the lower end of a rocker arm 98 on the outside of the frame member 11, as shown in Fig. 2. The rocker arm 98 carries a crank pin 99 connected to the link 97 which is adjustable transversely of the rocker arm by means of a handwheel and screw assembly 100. The rocker arm 98 is fixed at its upper end to a cross shaft 101 which extends between the plates 11 and 12 and carries corresponding levers 102 and 103 which are connected pivotally at their upper ends to the push rods 25 and 26, respectively. The push rods may have hingedly connected sections to permit them to follow the oscillation of the levers 102 and 103. Thus, as the crank disc 94a is rotated, the feed plate 24 is reciprocated below the hopper 20 to strip wafers from the hopper and deposit them in rows upon the conveyor 18. The adjustments referred to above enable the stroke and position of the plate 24 to be regulated.

The shaft 93 also carries a first cam 94 and a second cam 94b (Fig. 2) to control the movement of the depositing devices 29 and 30.

As indicated above, the manifold 32 is carried by means of slide blocks 60 and 61. As shown in

Fig. 1, the block 60 is slidably mounted between the parallel substantially horizontal rails 104 and 105 of a generally H-shaped slide member 106. The block 61 is similarly mounted in a slide member 107 on the opposite side of the machine.

The slide blocks 60 and 61 can move substantially parallel with the conveyor 18 in the frames 106 and 107. The corners of the frames 106 and 107 are provided with guide rollers 108 and 109, respectively, which engage vertical guide rails 110 and 111 on the side plate 11 and the guide rails 112 and 113 on the side plate 12. The H-shaped slide frames 106 and 107 move up and down while the slide blocks 60 and 61 therein can move horizontally. Up and down movement of the slide frames 106 and 107 is produced as follows. The cam 94 is provided with an eccentric cam track 114. This cam track 114 cooperates with an arm or lever 115 having a cam follower 115a thereon which engages in the cam track. The lever 115 is supported on a shaft 116. As the cam 94 rotates, the lever 115 is oscillated, thereby rocking the lever 117, to which it is connected by an adjustable length link 118. The lever 117 has a crank pin 119 connected to the link 118. The pin 119 is adjustable lengthwise of the lever by means of the screw and handwheel 120. The lever 117 is keyed at its upper end to the cross shaft 121 which extends between the frame plates 11 and 12. The shaft 121 carries near one end, as viewed in Fig. 2, a crank member 122 which is connected by means of a link 123 to a crank 124, on the cross shaft 125 so that these shafts rotate in unison. The ends of the shaft 121 carry the levers 126, 126, which have their outer ends connected by means of the links 127, 127 to the H-shaped frames 106' and 107', respectively, of the depositor 30. The shaft 125 carries the levers 128, which are connected by means of the links 129, 129 to the slides 106 and 107 of the depositing device 29. Thus, as the shafts 121 and 125 are rocked, the depositing manifolds of the depositors 29 and 30 are moved up and down with them.

Horizontal movement of the manifold is produced by means of the crank disc 94b, Fig. 2, which oscillates a lever 130 in the same manner that the lever 115 is moved by the cam 94. The lever 130 is supported rotatably on the shaft 116. The upper end of the lever 130 is connected by means of an adjustable link 131 to the lever 132 which is also provided with an adjusting screw and handle 133 to vary the spacing of the end of the link 131 from the axis of the supporting shaft 134. The shaft 134 carries at its opposite ends the upwardly extending levers 135 and 136 which are connected by means of the links 137 and 138 to the slide blocks 60 and 61 which carry the manifold 32. Links 139 and 140 also connect the levers 135 and 136 to the slide blocks 60' and 61' of the depositor 30. Rocking movement of the shaft by means of the cam 94b causes simultaneous movement of the manifolds of the depositors 29 and 30 parallel with the conveyor 18.

The various adjustments referred to above permit the timing of the manifolds with respect to the speed of the conveyor and also permit the up and down and horizontal movements of the depositing manifolds to be varied throughout a wide range. Preferably, the adjustments are made so that the manifolds 32 move downwardly toward the conveyor, then parallel with the conveyor while the slide valve 39 of the depositing manifold is opened by means of the cam members 142 and 142' on the side plate 12 to hold

the valve open (Figs. 2 and 4). The valve remains open during a part of the movement of the manifolds to the right in the same direction of travel as the conveyor and closes before the travel of the manifold is completed. The manifold 32 then moves upwardly stretching the streams of material between the conveyor 18 and the nozzles and breaking them to leave the usual tails standing up from the articles. The manifold is then moved to the left as viewed in Fig. 1 in a substantially horizontal plane and then toward the conveyor to complete another cycle. All of these movements are timed to the position and speed of the articles on the conveyor so that continuous movement of the conveyor is possible while intermittent depositing takes place on successive rows of cookies or the like carried by the conveyor.

Inasmuch as the whole assembly including the depositing manifold and the various slides are 20 light in weight, a very rapid repetition of the depositing cycle can take place without setting up excessive vibration in the machine so that a very high production rate is possible with the machine.

While two depositing devices 29 and 30 are disclosed in the drawings, it will be understood that only one such depositing device need be used on the machine for depositing a single type of material or several different kinds of material on the same or different cookies.

The dual type of depositor illustrated is useful when it is desired to deposit two different kinds of material on the same wafer, for example, marshmallow and jelly on the same wafer. The manifolds may be supplied from several separate sources as desired.

It will be understood that the apparatus may be used for depositing many different types of materials, and that its size and details of construction may be modified as the purpose demands. Therefore, the form of the invention described herein should be considered as illustrative and not limiting the scope of the following claims.

I claim:

1. A depositor comprising a tubular member having a plurality of nozzles, a closed system including flexible conduits to supply flowable material under pressure to said tubular member for discharge through said nozzles, valve means interposed between said nozzles and said tubular member movable to open and closed positions to permit and prevent, respectively, flow of said material through said nozzles, means supporting said tubular member for movement substantially horizontally and up and down, and mechanism operated in timed relation to move said tubular member substantially horizontally in one direction, open said valve during said movement, close said valve, move said tubular member upwardly and in the opposite direction, then downwardly and repeat the cycle.

2. A depositor comprising a tubular member having a plurality of downwardly extending nozzles, a closed system including flexible conduits to supply flowable material under pressure to said tubular member for discharge through said nozzles, valve means interposed between said nozzles and said tubular member movable to open and closed positions to permit and prevent, respectively, flow of said material through said nozzles, means supporting said tubular member for movement substantially horizontally and up and down, and mechanism operated in timed rela-

tion to move said tubular member substantially horizontally in one direction, open said valve during said movement, close said valve, move said tubular member up and in the opposite direction and then down and repeat the cycle.

3. A depositor comprising a frame, first slide means on said frame and movable up and down relative thereto, second slide means mounted on said first slide means and movable back and forth at substantially a right angle to said first slide means, a tubular member mounted on and movable with said second slide means and having a plurality of nozzles extending downwardly therefrom and connected to said tubular member by passages, a closed system including flexible conduits to supply material under pressure to said tubular member for discharge through said nozzles, valve means to open and close said passages, and mechanism to move said slide means and said valve in timed relation to cause said tubular member to move in one of said right angle directions while the passages are open, and then to close said passages and move said tubular member up and in the opposite right angle direction.

4. A depositor comprising a frame, a pair of substantially vertical guides on said frame on opposite sides of said frame, a slide member mounted in each pair of guides for up and down movement, guide elements on each of said slide members extending substantially perpendicular to said guides, a tubular member having a plurality of downwardly extending nozzles, valve means interposed between said tubular member and said nozzles, said valve means being movable between open and closed positions to permit and prevent communication between said tubular member and said nozzles, means at opposite ends of and fixed to said tubular member slideable in said guide elements, mechanism to move said slide members up and down in said guides, mechanism to move said tubular member back and forth along said guide elements, mechanism to open and close said valve means, and drive means to operate said mechanisms in timed relation to open said valve means as said tubular member moves in one direction in said guide means, and close said valve means as said tubular member moves in the opposite direction and said slide members move up in said guides.

5. The depositor set forth in claim 4, comprising a distributing manifold fixed to said frame, at least one flexible conduit connecting said manifold to said tubular member to permit relative movement therebetween, and means to supply flowable material under pressure to said manifold.

6. A depositor comprising a frame, two pairs of guide members on said frame on each side thereof, said guide members being substantially vertical, a slide member mounted between each pair of guide members for movement up and down relative to said frame, a supporting member mounted slidably in each slide member for movement back and forth substantially perpendicular to said guide members, a pair of tubular members having depositing nozzles thereon extending transversely of said conveyor and each having its end portions connected to a different supporting member on opposite sides of said frame, crank means for moving said slide members simultaneously up and down, crank members on opposite sides of said conveyor connected to the supporting members to move them back and forth simultaneously in the same direction,

and means connecting said crank means and crank members to each other to cause said tubular members to move along closed paths, parts of which are substantially horizontal.

7. A depositor comprising a source of flowable material to be deposited, means to maintain said material at a pressure substantially higher than atmospheric pressure, an elongated tubular manifold having a row of spaced apart openings extending lengthwise thereof, closures for the ends of said manifold, flexible means connecting said source of material to said manifold to introduce flowable material at superatmospheric pressure into said manifold at spaced apart points along the length of said manifold, a row of nozzles mounted on said manifold, each of said nozzles being substantially in alignment with one of said openings, and a slide valve member having openings therein corresponding to said nozzles interposed between said nozzles and said manifold, said slide valve member being movable to position the openings therein selectively in alignment, and out of alignment, with the openings in said manifold and said nozzles.

8. A depositor comprising a source of flowable material to be deposited, means to maintain said material at a pressure substantially higher than atmospheric pressure, a fixed distributing pipe connected to said source to receive said material therefrom at said higher pressure, an elongated tubular manifold having a plurality of spaced apart openings in a row extending lengthwise of said manifold, means supporting said manifold for movement transversely of its axis, closures for the ends of said tubular manifold, a row of nozzles mounted on said manifold, each of said nozzles being substantially in alignment with a separate opening in said row, a slide valve member having openings therein corresponding to said nozzles interposed between said nozzles and said tubular manifold, said slide valve member being movable to position the openings therein selectively in and out of alignment with said nozzles and the respective openings in said manifold, a plurality of couplings spaced apart lengthwise of said manifold, and flexible conduits connected to said manifold and said distributing pipe to introduce flowable material into said manifold under pressure for discharge through said openings therein and said nozzles and allow movement of said manifold relative to said distributing pipe.

9. A depositing head comprising an elongated tubular manifold having a plurality of spaced apart openings in a row extending lengthwise of said manifold, a plurality of couplings spaced lengthwise of said manifold to introduce flowable material under pressure into said manifold, closures for the ends of said tubular manifold, a row of nozzles mounted on said manifold, each of said nozzles being substantially in alignment with a separate opening in said row, a slide valve member having openings therein corresponding to said nozzles interposed between said nozzles and the row of openings in said manifold, said slide valve member being movable to position the openings therein selectively in alignment with said nozzles to discharge material from said manifold through said nozzles and out of alignment with said nozzles to prevent discharge of

material through said nozzles, a rod engaging at its opposite ends and held against endwise movement by said end closures and a plurality of thin plates fixed to said rod and fitting the interior of said tubular manifold and spaced apart to be disposed between said couplings and between said nozzles to divide said tubular manifold into compartments, each of which communicates with one coupling and at least one nozzle.

10. A depositing head comprising an elongated tubular manifold having a series of holes therein, means to introduce material into said manifold, under pressure, a row of nozzles on and communicating with the interior of said tubular manifold through said holes and a slide valve member having openings therein corresponding to said nozzles, said slide valve member being interposed between and slidable relative to said nozzles and said tubular manifold to position the openings in said slide valve member into and out of alignment with said nozzles, said nozzles being rotatably mounted on said tubular manifold on axes offset laterally from the corresponding holes in said manifold, each nozzle having a central passage, the inlet end of which is eccentric to the axis of rotation of said nozzle to enable it to be moved into and out of alignment with the corresponding holes in said manifold and into partial alignment therewith to adjust the rate of discharge from the manifold through said nozzles.

11. A depositing head comprising an elongated tubular manifold having a plurality of spaced apart openings in a row extending lengthwise of said manifold, a plurality of couplings spaced lengthwise of said manifold to introduce flowable material under pressure into said manifold, closures for the ends of said tubular manifold, a row of nozzles mounted on said manifold, each of said nozzles corresponding to a separate opening in said row, a slide valve member having openings therein corresponding to said nozzles interposed between said nozzles and the row of openings in said manifold, said slide valve member being movable to position the openings therein selectively in alignment with said nozzles to discharge material from said manifold through said nozzles and out of alignment with said nozzles to prevent discharge of material through said nozzles, each of said nozzles being rotatably mounted on said tubular manifold, the axis of rotation of each nozzle being offset with respect to the corresponding opening in said manifold, and each nozzle having a central passage, the inlet end of which is eccentric to the axis of rotation of said nozzle to enable it to be moved into and out of alignment and into partial alignment with the corresponding hole in said manifold by rotation of said nozzle to adjust the rate of discharge from the manifold through each nozzle.

EARLE T. OAKES.
